UNITED STATES PATENT OFFICE

WILLIAM NICHOLAS THODE, OF CHICAGO, ILLINOIS, ASSIGNOR TO WESTERN ELECTRIC COMPANY, INCORPORATED, OF NEW YORK, N. Y., A CORPORATION OF NEW YORK

CASTING APPARATUS

Application filed May 13, 1926. Serial No. 108,811.

This invention relates to casting apparatus, and more particularly to die casting apparatus.

The objects of this invention are to provide a casting apparatus which may be expeditiously and effectively connected with and disconnected from a die or mold.

In order to obtain these and other objects and in accordance with the general features of the invention, one embodiment thereof comprises a furnace or oven and a melting pot associated therewith. A detachable connecting member having a communicating passageway is provided, which is designed to interconnect a charging chamber of the melting pot and a fixed die or mold. This connecting member is adapted to be wedged in operative position between and to make a wiping contact with the melting pot and the associated die or mold, thereby establishing a communication between the melting pot and die. A mechanism is also provided whereby the connecting member may be effectively connected and disconnected.

These and other objects will be apparent from the following detailed description when considered in connection with the accompanying drawing, in which—

Fig. 1 is a central fragmentary vertical section of a die casting apparatus disclosing one embodiment of the invention with the connecting member thereof shown in its inoperative or disengaged position, and

Fig. 2 is a fragmentary plan view of the apparatus shown in Fig. 1.

Referring now to the drawings wherein like numerals designate similar parts throughout the figures, the improved casting apparatus includes a furnace designated generally by the numeral 10. This furnace 10 and its associated parts are very similar in construction and operating characteristics to the structures disclosed and described in the copending application of Frederic Shields Kochendorfer, Serial No. 108,783, filed May 13, 1926, and comprises a cylindrical oven 11 hingedly mounted at one point upon a suitable base plate 12. Coil springs 13 encircling companion plunger members 14 threaded into the base plate 12 supply a resilient sup-

port for the oven 11 and permit it to experience a swinging movement about its hinged mounting in a manner and for a purpose later to be explained. The oven 11 is provided with a refractory lining 16 and extending through the cylindrical sections of this lining 16 at spaced intervals is a plurality of heating elements or burners 17 which are suitably connected with a source of gas supply (not shown). Mounted upon the base plate 12 and reaching upwardly therefrom into the oven 11 is a post 18 which serves as a prop or support for a melting pot 19 which is designed to be heated by flames from the burners 17.

This melting pot 19 which is marginally supported at the upper end of the refractory wall 16 of the oven 11, is formed with a supply compartment or chamber 21 and an elongated U-shaped charging chamber 22. This charging chamber 22 is disposed beneath and along the side of the supply chamber 21, one end thereof being threaded to receive a coupling 23 of a conventional air pressure valve (not shown), and the other end thereof terminating within a filling chamber 25. The filling chamber 25 communicates with the lower portion of the supply chamber 21 through a conduit 26 and thus it will be apparent that material placed within the supply chamber upon becoming molten will flow through the conduit 26 and into the filling chamber 25. The molten material from within the filling chamber 25 will be free to flow into the charging chamber 22 when a connecting member or nozzle 28 assumes its inoperative or disengaged position as shown in Fig. 1.

The connecting member 28 is provided with an arcuate passageway 30 and is pivotally connected at its upper portion with one extremity of a toggle arm 31. The toggle arm 31 is pivoted at its opposite extremity to a companion toggle arm 32, which is in turn secured to a transverse horizontal rock shaft 33. The rock shaft 33 which extends immediately above and transversely of the melting pot 19 is rotatably mounted at its extremities in suitable fixed bearing members 34, and one end of the rock shaft is provided with an actuating lever 36. When the actuating lever 100

36 assumes the position shown in Figs. 1 and 2, the knee of the toggle arms 31 and 32 will be broken and the connecting member 28 will consequently occupy its raised or inoperative position as shown. Raising the actuating lever 36 causes the connecting member 28 to be lowered with the result that a concave surface 37 at the outer end of the connecting member 28 is carried into wiping engagement 5 with a companion spherical surface 38 of a suitable die 39 fixed in position upon a die support 40. Contemporaneously with the engagement of the above mentioned surfaces, a convex surface 42 of the connecting member 28 is likewise carried into wiping engagement 10 with a companion concave surface 43 in the bottom of the filling chamber 25. Thus when the toggle arms 31 and 32 are in alignment, the connecting member 28 will be firmly 15 wedged into position between the egress opening of the charging chamber 22 and the inlet to the die 39, as shown by the dotted lines (Fig. 1). When the connecting member 28 is in this position the arcuate passage- 20 way 30 thereof serves to establish a communication between the charging chamber 22 and the mold within the die 39. In this connection it is to be understood that the coil springs 13 which support the oven 11 lend a 25 sufficient resilient response to permit of the wedging of the connecting member 28 and cooperate to effect the wiping or sliding engagement of the concave surface 37 with the convex spherical surface 38 and the convex 30 surface 42 with the concave surface 43 as above mentioned.

When the charging chamber 22 has been 35 sufficiently charged with a supply of molten material, the connecting member 28 may be lowered into its operative position by the actuation of the lever 36. It will be apparent that a certain amount of molten material will be present within the filling chamber 25 when the connecting member is being lowered 40 to its operative position and by reason of the wiping engagement made by the connecting member within the filling chamber, molten material will be squeezed from between the contacting surfaces so as to make 45 a very tight and firm connection. Subsequent to the lowering of the connecting member 28, air pressure is supplied through the coupling 23 from a suitable source of air supply (not shown) and the molten material 50 from within the chamber 22 is forced through the passageway 30 of the connecting member 28 and into the die 39. The air pressure is then discontinued and the connecting member 55 may again be raised to permit of the recharging of the chamber 22 and the replacement of the die 39. In this connection it will be noted that the surface of the molten metal within the filling chamber 25 may be 60 maintained at a high level so that the inner

end of the connecting member will constantly be immersed.

In the operation of the casting apparatus the connecting member 28 is elevated to its inoperative position and material to be cast is placed within the supply chamber 21 of the melting pot 19 through an opening 46 provided at the upper portion thereof. Burners 17 are ignited and as the material within the supply chamber becomes molten it will flow through the conduit 26 into the filling chamber 25 and thence downwardly into the charging chamber 22. The die 39 is properly positioned upon the support 40 and when the chamber 22 has been sufficiently charged the actuating lever 36 is raised upwardly to the connecting member 28. The engaging surfaces 37 and 42 of the connecting member make a wiping contact with the companion surface 38 of the die 39 and the surface 43 of the melting pot 19 and the connecting member is thus firmly wedged into position therebetween. Air pressure is then applied to the coupling 23 and the charge of molten metal within the chamber 22 is forced 90 into the mold of the die 39. In this connection attention is directed to baffles 44 formed upon a portion of the connecting member positioned within the filling chamber 25, and also a baffle 45 formed integral with the melting pot within the filling chamber. These baffles serve as an added safeguard to prevent the scattering of molten material from the filling chamber in the event that the convex surface 42 does not 95 make a perfect contact with its companion concave surface 43.

Although the invention as herein illustrated and described is particularly well adapted for use in connection with die casting apparatus, it should be understood that the novel features thereof are capable of other applications and should be limited only by the scope of the appended claims.

What is claimed is:

1. In a casting apparatus, means for retaining material to be cast, a mold, a connecting member, and means attached to the member for causing a wiping engagement of the member with the material retaining means to effect the interconnection of the material retaining means and the mold.
2. In a casting apparatus, a substantially stationary means for retaining material to be cast, a mold, a connecting member, and means for causing a wiping engagement of the member with the material retaining means and the mold to establish an interconnection therebetween.
3. In a casting apparatus, a substantially stationary means for retaining material to be cast, a mold, a connecting member, and means for causing a relative movement between the member and the material retaining means to effect a wiping engagement of the connecting

member with the material retaining means and the mold.

4. In a casting apparatus, means for retaining material to be cast, a mold, a connecting member, and means attached to the member for wedging the member between the retaining means and the mold to afford communication between the mold and the retaining means.

5. In a casting apparatus, means for retaining material to be cast, a mold, a connecting member, and means for wedging the member between and for making a wiping engagement with the retaining means and the mold.

6. In a casting apparatus, means for retaining material to be cast, a mold, a movable member for interconnecting the material retaining means and the mold, and a toggle mechanism attached to the member and adapted to effect the making and breaking of the interconnection of the movable member.

7. In a die casting apparatus, means for retaining a charge of material to be cast, a die, a connecting member, and means for causing the member to engage with the die and the retaining means, said retaining means being yieldingly responsive to the engaging action of the connecting member.

8. In a die casting apparatus, means for retaining a charge of material to be cast, a fixed die, a movable connecting member, and a toggle mechanism for causing the member to make a wiping engagement with and a wedging interconnection between the die and the material retaining means.

35 9. In a die casting apparatus, a material retaining means including supply and charging chambers, a die, a member for interconnecting the charging chamber and the die, and means for disconnecting the member from the charging chamber to permit the charging chamber to be charged with material from the supply chamber.

10. In a casting apparatus, a mold, means for holding a supply of the material to be cast, means stationary with respect to the supply means for retaining a charge of the material, and movable means for effecting the charging of the retaining means and having a passage for connecting the charging means with the mold.

55 11. In a casting apparatus, a mold, means for retaining a supply of material to be cast, integral means connected therewith for retaining a charge of the material, and means for disconnecting the supply means from the means for retaining the charge and interconnecting the mold therewith.

12. In a casting apparatus, a mold, means for retaining a charge of material to be cast, a material supply means mounted thereon and having a passage connecting with the retaining means, and an interconnecting means for connecting the retaining means and the mold and for closing the passage in the supply means.

13. In a casting apparatus, a mold, a material supply means, means for retaining a charge of material to be cast as received from the supply means, and means for controlling the flow of the material to the retaining means and for connecting the mold with the retaining means.

In witness whereof, I hereunto subscribe my name this 29th day of April, A. D., 1926.

WILLIAM NICHOLAS THODE.
